UNITED STATES PATENT OFFICE.

HARRY J. KNOPKE, OF RACINE, WISCONSIN.

DOOR AND WINDOW LOCK.

Application filed April 11, 1922. Serial No. 551,450.

To all whom it may concern:

Be it known that I, HARRY J. KNOPKE, a citizen of the United States, residing at Racine, in the county of Racine and State 5 of Wisconsin, have invented certain new and useful Improvements in Door and Window Locks, of which the following is a specification.

This invention relates to locking devices, 10 and especially to an improved door and window lock, the same being of the class known as "closure fasteners,—braces,—portable."

One object of this invention is to provide 15 a device of this character having excessive strength consistent with comparative lightness and compactness.

Another object is to provide a device of 20 this character in which the brace or prop operates to automatically re-engage its keeper in the event it is accidentally or purposely disengaged therefrom but not moved to the position for securing it in the inoperative or folded position.

Another object is to provide a device of 25 this character with frictional means for securing its prop in the inoperative and out-of-the-way position.

Another object is to provide a device of 30 this character in which the main body or frame portion is formed of a single blank of sheet metal, so that the device can be manufactured at the minimum cost.

Other objects and advantages will be 35 pointed out or implied in the following details of description, in connection with the accompanying drawings in which:

Fig. 1 is a side elevation of the device, in 40 one of its forms, folded for convenience in carrying or packing for shipment.

Fig. 2 is a top plan view of the device shown in Fig. 1, a part being shown in horizontal section.

Fig. 3 is a vertical sectional view showing 45 the device applied as a door-lock or fastener.

Fig. 4 is an enlarged detail view for more 50 clearly showing the eccentric arrangement for effecting the result mentioned in the third paragraph of the foregoing statement of the "objects."

Fig. 5 is a side elevation of a slightly 55 modified form of the invention applied to a door, the door and floor being shown in section.

Fig. 6 is an enlarged detail view showing

a longitudinal section and a transverse section of an abutment formed from a blank of sheet material.

Fig. 7 is a side elevation of another modified form of the invention, the same being applied to a window, parts of the latter being shown in section.

Fig. 8 is a top plan view of the device shown in Fig. 7.

Fig. 9 is a longitudinal vertical section of the device shown in Figs. 7 and 8, the pawl or prop being omitted.

Fig. 10 is a plan view of the base or attaching plate of the device shown in Figs. 7, 8 and 9.

Fig. 11 is a plan view of a blank to form the main body or frame of the device shown in Figs. 7, 8, 9.

Referring to these drawings in detail, in which similar reference characters correspond to similar parts throughout the several views, and in which the parts of door, floor and window are shown merely to illustrate the applications of the device; the invention consists in the construction and arrangement or combination or elements which will now be fully explained in the following:

The main body or frame 1^a, 1^b and 1^c, is preferably formed from a single blank of sheet metal or material, and the abutment 2 may also be formed from a blank of sheet material, as shown at 2^a in Fig. 6 although it is shown as a block in the other figures of the drawings. The pawl or prop 3 is preferably of strong and rigid metal and formed with a cylindrical end 4 which is eccentrically apertured at 5 to receive and swing on a pin or pivot 6 which extends through the parallel walls of the channel-bar which constitutes the body 1^a, 1^b, 1^c. These walls of the channel-bar are projected beyond the floor bottom or connecting plate of the channel-bar for a purpose which will presently be explained, and it is in these projections of the walls that the pivot 6 is secured: However, this description only applies, literally, to the form shown in Figs. 1, 2 and 3, but the same principle is employed in the other forms, as will presently appear: For instance, in Fig. 5 the floor 7 is united with a securing strip or plate 8 which extends past the adjacent ends of the channel-walls and thence turns at right angles to the floor for engagement with the lower edge of the door; but the connecting plate terminates at 10 as it does in Figs. 1

105 110

and 3. Spurs 11 may be provided to engage or pierce the lower edge of the door and co-operate with a screw 12 for securing this form of the invention in place. In 5 lieu of the elements 8, 9 and 11 of Fig. 5, I may provide a stud or boss 13 (Figs. 1, 2, 3, 4) which may be seated or fitted in a cavity made for receiving it in the door (see Fig. 3). This boss is preferably united 10 with a pin or rivet 14 which extends through registering apertures in the members 1^a and 2 for uniting these members with one another and with the boss 13. When thus united, they become a unitary unchanging 15 member, and are made separately, instead of integrally, for economy of manufacturing. The member 13 cooperates with the screw 12 for holding the device in the door.

Referring now to Fig. 4, it will be seen 20 that the pivot 6 is further from the periphery of the lower side of the cylindrical part 4 than it is from the upper part; or in other words, the eccentricity of the pivot 6 is such that when the pawl or prop 3 is in its operative position (Fig. 3) it is free to move 25 by gravity, so that if the door is moved past its normal "closed" position, the pawl will automatically engage its keeper when it returns to the normal position. On the other 30 hand, when the pawl or prop 3 is raised or swung to the folded position shown in Figs. 1 and 4, it will (because of its eccentricity) frictionally engage with the concaved end or frictional detent 16 or 16^a, and especially 35 with the lower end thereof, and bind the pawl or prop in its folded position. The eccentricity of the pin 6, with respect to the cylinder 4, is only a few thousandths of an inch, and is exaggerated in the drawings for 40 the sake of obviousness; so if the device is accurately constructed, this frictional binding effect would obtain in consequence of the slight yielding of the comparatively rigid elements even if the connecting plate 7 extended 45 to the end of the abutment 2; but to provide for possible inaccuracies of manufacture, I may extend the comparatively springy end 16^a beyond the end 10 of the floor or connecting plate 7, thus providing a 50 clearance for permitting the part 16^a to yield to the pressure of the eccentrically pivoted cylindrical end 4. An aperture 17 is provided in the connecting plate 7 of the device shown in Figs. 7 to 11 inclusive, this aperture 55 providing the clearance for the frictional detent 16^a.

In the form illustrated in Figs. 7 to 11 inclusive, a plate or base 18 is provided with screw-holes 19 through which screws 20 may 60 be passed for securing the device to the upper part of a window-sash, as shown in Fig. 7. Fig. 9 shows this plate pivoted to the body 1^c and abutment 2 by means of a rivet 14 whose head 13 is imbedded in the lower 65 sash for co-operating with the screws 20 for

securing the device against displacement. The rivet 14 extends through registering apertures 21 and 22 of the plates 18 and 7; and the pivot 6 extends through apertures 5 as it does in the other forms of the invention. 70 The floor or plate 7, of this form of the invention, is preferably formed with arcuate wings 23 which are preferably struck up from openings 24 of the blank shown in Fig. 11. In this figure the openings 24 appear as 75 mere arcuate slits, but when the blank is formed by bending along the lines 5, for making the parallel walls of the channel-bar or body 1^c, then the slits 24 are opened to form the openings 24 of Figs. 7 and 9. 80 These wings 23 combine with the intervening part of the connecting plate to form a circular plate or disk whose perimeter registers with the main marginal portion of the plate 85 18, thus providing symmetry and stability. 95

For the purpose of co-operating with the elements 3 and 15 in securing the upper and lower sashes against relative movement, and for the further purpose of preventing rattling of the sashes, I provide an angular extension 24^a of the connecting plate 7, and a slot or recess 25 is formed in the upright part of this extension for engaging a screw or keeper 26. The recess is open at one edge of the part 24^a so that it passes into engagement with the keeper 26 when the body 1^c is swung around on the base 18, provided the sashes have first been placed in the proper relation to one another. The keeper 15 of Figs. 3, 5 and 7 may be (and is preferably) 100 in the form of a cylinder-headed screw, as shown, the top thereof being flush with the surface in which it is imbedded.

It is not intended to limit this invention to the exact construction and arrangement 105 here shown and described, but changes may be made within the scope of the inventive idea as implied and claimed.

What I claim as my invention is:

1. In a door or window fastener, the combination of an elongated member which is channel-shaped in cross-section and provided with means to secure it to a door or window, a keeper securable to a floor or other object near the door or window, a prop formed with a cylindrical end which is pivotally mounted in one end of said channel-shaped member, the other end of said prop being engageable with said keeper, and an abutment having a concaved end and being secured in said channel shaped member in such position that its concaved end is in contiguity with said cylindrical end and adapted to bear against the latter for the purposes specified. 115

2. The combination defined in claim 1, and a fastening member including a shank and a cylindrical head, the latter being seatable in a cylindrical cavity in the door or window for aiding in securing the fastener on the door or window, said shank being extended 120

through said channel-shaped member and abutment for securing them together.

3. In the combination defined in claim 1, the pivot of said cylindrical end being eccentric to the periphery of said cylindrical end, substantially as shown and for the purposes specified.

4. In the combination defined in claim 1, the channel-shaped member being formed with a clear space at the opposite side of the said concaved end from said cylindrical

end, substantially as shown and for the purpose specified.

5. The combination defined by Claim 1, a base on which the said channel-shaped member is pivotally mounted, and a second keeper, means being provided for connecting said channel-shaped member with said second keeper.

In testimony whereof I affix my signature. 20

HARRY J. KNOPKE.
